UNITED STATES PATENT OFFICE.

ANTONIO MURINO, OF NEW YORK, N. Y.

VALVE FOR AUTOMATIC PIANO-PLAYERS.

No. 862,002.

Specification of Letters Patent.

Patented July 30, 1907.

Application filed June 23, 1905. Serial No. 266,608.

To all whom it may concern:

Be it known that I, ANTONIO MURINO, a citizen of the United States of America, residing at New York, in the county of New York and State of New York, have 5 invented new and useful Improvements in Valves for Automatic Piano-Players, of which the following is a specification.

The invention relates to an improvement in automatic piano players and particularly to a novel valve 10 construction therefor.

The main object of the present invention resides in the production of a valve for use in automatic piano players and designed to automatically control the admission of air to the key operating mechanism, whereby 15 to regulate the operating force of said mechanism and thereby the loudness of tone produced.

The invention consists in certain details of construction and combination of parts, which will be described in the following specification, reference being had particularly to the accompanying drawings, in which:

Figure 1 is a vertical sectional view of one end of the piano player, illustrating the valve controlling mechanism constructed in accordance with my invention. Fig. 2 is a vertical transverse section of the same. Fig. 25 3 is an enlarged broken vertical section of the valve structure.

Referring to the drawings, 1 represents the box of any desired pipe or piano player, divided horizontally into chambers 2, 3, 4 and 5, each of which chambers 4 and 5 30 is divided by vertical partitions 6, providing independent chambers equal in number to the number of keys of the piano, and each containing a controlling valve mechanism. It is to be understood that the chambers 2, 3, 4 and 5 are in vertical alignment, and together 35 constitute a single operating set for the key of the piano. The chamber 2, hereinafter termed the controlling chamber, is located at the lower end of the box 1, and is of less diameter than the remaining chambers. The controlling chamber is in communication with the 40 atmosphere through the usual tube 7, the inlet being controlled by the openings in the music sheet. The chamber 4, hereinafter termed the valve chamber, is at all times in direct communication with the exhaust bellows (not shown) and designed to be constantly under the influence of the said bellows, as is usual. The chamber 4, hereinafter termed the valve chamber, is 45 in direct communication through a channel 8 with the key operating mechanism, shown in the present instance as an operating bellows 9.

50 The present invention is directed to a valve mechanism designed to control the admission of air to the exhaust chamber 3 from the valve chamber 4 whereby to draw a greater or less quantity of air from the key operating mechanism and thereby regulate the active force

of said mechanism. To this end my valve mechanism 55 comprises a flexible diaphragm 10 overlying the edges of the controlling chamber 2 and sealing the same against the exhaust chamber 3, this diaphragm being secured in any desirable manner to insure a complete sealing of this chamber, with the exception of a small 60 bleed opening 10'. The diaphragm is centrally perforated to receive the reduced end 11 of a valve stem 12, securing washers 13 encircling the reduced portion 11 of the valve stem on each side of the diaphragm, whereby to secure said stem in place and provide for 65 the ready operation of the valve.

Beyond the portion 12 the valve stem is enlarged at 14 to form a cylindrical body longitudinally slotted at 15, said body being of a length to normally project through an opening in the partition intermediate the 70 exhaust and valve chambers, the upper end of the body being provided with a reduced vertically extending stud 16, designed to receive a valve disk 17, of greater diametrical extent than the body and serving to contact with the upper surface of the horizontal partition 75 between the exhaust and valve chambers and thereby limit the downward movement of the body. By preference the disk 17 is of sectional formation and of such material as to provide for positively sealing the opening in said partition when the valve is in normal or closed 80 position.

The stud 16 is longitudinally bored at 18, and internally threaded to adjustably receive the threaded lower end of the adjusting rod 19, which extends vertically through the valve chamber 4 and chamber 5, 85 terminally projecting beyond the upper wall of the box and being there provided with a handle end 20, preferably formed by suitably bending the rod, as illustrated. 21 presents a stop, preferably circular in plan and designed for threaded engagement with the adjusting rod 19, said stop being located within the valve chamber 4 and under normal conditions spaced a slight distance from the transverse partition between chambers 4 and 5. By this arrangement the valve is permitted an upward movement coextensive with the 90 space normally existing between the stop 21 and the partition between chambers 4 and 5, as will be evident.

The longitudinally arranged slot 15 in the body 14 extends entirely through said body and is of a length to terminate just below the stop or valve disk 17, so that 100 when said collar is in normal position, said slot is closed against the valve chamber.

It is to be understood, of course, that the exhaust bellows constantly causes exhaust in the chamber 3, which will when the body 14 is elevated, act through 105 channel 8 and bellows 9 to collapse said bellows, and that upon the closing of the disk carried by body 14 and the opening of the valve disk 17 the air under atmos-

pheric pressure will pass through the opening in the partition between chambers 4 and 5 and restore the bellows to normal condition.

- The operation of my improved valve is as follows:
- 5 The air under atmospheric pressure, admitted through the tube 7 to the chamber 2, by register of the openings in the music sheet into said tube, will force the central portion of the diaphragm upward, thereby moving the body and causing the open end of its slot 15 to project
  - 10 within the valve chamber, while the lower end of said slot remains within the exhaust chamber. Communication is thus established between the exhaust and valve chambers and the air from the latter will be drawn through the latter and thence to the exhaust bellows.
  - 15 Under the influence of the air in the controlling chamber the body will be vertically moved until the disk 17 contacts with the partition between chambers 4 and 5, and as the stop 21 which supports the disk 17 is vertically adjustable with the relation to the body 14, 20 through an obvious operation of the adjusting rod 19, it is evident that I may readily control the quantity of air exhausted in a given time from the bellows 9, and thereby readily regulate the volume of tone produced. Upon cessation of the pressure within the controlling
  - 25 chamber the parts return to normal position, shutting off communication between the exhaust chamber and the valve chamber.

The valve parts are few in number and the valve as a whole, simple in construction, the arrangement being such as to be readily adjustable to provide for the volume desired.

Having thus described the invention, what I claim is—

A piano player including an exhaust mechanism and key operating mechanism and comprising an exhaust chamber in communication with the exhaust mechanism, a valve chamber in open communication with the key operating mechanism and formed with an atmospheric vent, a controlling chamber arranged below the exhaust chamber, a diaphragm closing the controlling chamber against the exhaust chamber, a valve operable in the valve chamber and normally closing the latter against the exhaust chamber, and a stem depending from said valve and connected of the diaphragm, said stem being formed with a transversely disposed port opening through the walls of the stem, a rod adjustably connected to the valve and extending through and beyond the valve chamber, and a stop secured on the rod and operating to control the atmospheric vent from the valve chamber, said stop serving to limit upward movement of the valve and permit arrangement of the port of the valve stem to provide communication between the exhaust chamber and valve chamber.

In testimony whereof, I affix my signature in presence of two witnesses.

ANTONIO MURINO.
